BOLT-ACTION FIREARM

David M. Williams, New Haven, Conn., assignor to
Olin Industries, Inc., a corporation of Delaware

Application June 24, 1944, Serial No. 541,904

4 Claims. (Cl. 42—70)

1

The present invention relates to improvements in firearms and relates more particularly to improvements in bolt-action firearms of the type wherein a breech-bolt has both longitudinal reciprocating movement and transverse turning movement.

In firearms of the type above referred to, it is essential that the firing-plunger be retracted with reference to the cartridge-seat in the forward face of the breech bolt, in order to avoid having such firing-plunger engage with the primer of a fresh cartridge as the latter is forced into the cartridge-chamber of the firearm by the breech-closing movement of the breech-bolt. As will be apparent from the following, the present invention involves a construction and arrangement of parts whereby the retraction of the firing-plunger referred to may be assured.

One of the objects of the present invention is to provide a bolt-action firearm of the type referred to, wherein superior means is provided for retracting a reciprocating firing-plunger with respect to a breech-bolt, to guard against having such firing-plunger available for engagement with the primer of a cartridge until the cartridge is substantially fully seated in the cartridge-chamber of the firearm and until the breech-bolt is locked.

Another object of the present invention is to provide a superior construction and arrangement of parts of the general character set forth above and further characterized by economy and simplicity of manufacture.

A further object of the present invention is to provide a bolt-action firearm with superior retracting-means for the firing-plunger so constructed and arranged as to avoid interference with a hammer and to enable the said hammer to strike a solid blow upon the firing-plunger.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a broken view of the central portion of a gas-operated self-loading firearm embodying the present invention, viewing the same from the right side, partly in side elevation and partly in vertical central-longitudinal section;

Fig. 2 is a similar view but viewing the structure from the left side and showing a portion of the receiver broken away, the parts being shown

2

in the positions which they assume immediately following the discharge of the firearm;

Fig. 3 is a view similar to Fig. 2 but showing the hammer in its cocked position, the breech-bolt in a position slightly rearwardly of its breech-closing position, and the firing-plunger in its retracted position;

Fig. 4 is a transverse sectional view taken on the line 4—4 of Fig. 2 and, therefore, showing the breech-bolt in its breech-closing position;

Fig. 5 is a view similar to Fig. 4 but taken on the line 5—5 of Fig. 3 and, hence, showing the breech-bolt in its unlocked position;

Fig. 6 is a top or plan view of the unit comprising the breech-bolt, firing-plunger and extractor;

Fig. 7 is a view looking toward the left side thereof;

Fig. 8 is a transverse sectional view on an enlarged scale, taken on the line 8—8 of Fig. 7;

Fig. 9 is a transverse sectional view taken on the line 9—9 of Fig. 6 and showing the guide-head of the firing-plunger in alignment with the adjacent locking-lug of the breech-bolt;

Fig. 10 is a view similar to Fig. 9 but showing the firing-plunger turned to bring its guide-head out of alignment with the adjacent locking-lug of the breech-bolt;

Fig. 11 is a view of the breech-bolt and associated elements partly in plan and partly in central-longitudinal section on the line 11—11 of Fig. 7;

Fig. 12 is a broken top or plan view of the forward portion of the receiver;

Fig. 13 is a view thereof in vertical central-longitudinal section taken on the line 13—13 of Fig. 12;

Fig. 14 is a view in front-end elevation of the firing-plunger, detached; and

Fig. 15 is a top or plan view thereof.

The particular bolt-action firearm herein chosen for illustration to make clear one embodiment of the present invention, is of the gas-operated self-loading type, though the present invention is applicable to manually-operable and other firearms wherein an oscillating-and-reciprocating breech-bolt is employed in conjunction with a firing-plunger.

The bolt-action firearm shown in the accompanying drawings includes among its main elements a receiver 15, a barrel 16, a trigger-plate unit 17, an action-slide 18, a stock 19 and a reciprocating-and-oscillating breech-bolt 20, which latter is accommodated in the upper portion of

a bolt-receiving chamber 21 formed in the interior of the receiver 15.

Adjacent its rear end, the barrel 16 is formed with an integral depending cylinder-lug 22 having a rearwardly-opening piston-chamber 23 therein. The said piston-chamber is arranged with its longitudinal axis extending in substantial parallelism with the bore 24 of the barrel 16. Leading forwardly and upwardly from the rear face of the front wall of the said piston-chamber 23 to the bore 24 of the barrel 16, is an inclined gas-passage 25 serving to conduct gas under pressure from the said bore to the piston-chamber 23 for the actuation of a piston in a manner as will hereinafter appear.

Mounted for reciprocation in the piston-chamber 23 of the cylinder-lug 22 is the relatively-large-dia-metered forward-portion 26 of a piston generally designated by the reference character 27. In addition to its forward-portion 26, the said piston 27 includes a rearwardly-projecting stem 28 resulting in the formation on the piston of a conically-contoured rearwardly-facing stop-shoulder 29. The stem 28 extends through and rearwardly beyond a ring-like stop-member 30 threaded or otherwise mounted within the threaded rear-portion of the piston-chamber 23 and formed with a conically-contoured forwardly-facing seat 31 adapted to be engaged by the similarly-contoured stop-shoulder 29 of the piston 27.

The rear face of the stem 28 of the piston 27 is normally engaged by the forward face of a front-head 32 constituting an integral feature of the action-slide 18 before referred to. The said action-slide also includes a rear-head 33 which is guided for reciprocation adjacent the right side of the receiver 15. The front-head 32 and the rear-head 33 of the action-slide 18 are integrally connected by a side-bar 34 extending in substantial parallelism with the longitudinal axis of the firearm-structure, as is especially well shown in Fig. 1. The rear-head 33 is formed with a laterally-projecting operating-handle 35 by means of which the firearm may be manually operated.

In its inner or left face, the rear-head 33 of the action-slide 18 is formed with a cam-recess 36 into which fits the outer portion of a combined operating-and-locking lug 37 laterally offsetting 38 from the forward end of the breech-bolt 20. The coaction of the lug 37 and the surfaces of the cam-recess 36 serve to operatively interconnect the action-slide 18 and the breech-bolt 20 in a manner broadly similar to the connection employed in the well-known Garand military rifle. The action-slide 18 (and hence, also, the breech-bolt 20) is yieldingly urged forwardly by a helical breech-closing spring 38 encircling and thrusting forwardly upon a breech-closing plunger 39 having its forward end seated against the front-head 32 of the action-slide 18, as is shown in Fig. 1. Normally, the breech-closing spring 38, acting through the breech-closing plunger 39, maintains the forward face of the front-head 32 of the action-slide 18 in engagement with the rear face of the stem 28 of the piston 27 and, in turn, serves to maintain the forward end of the said piston against the front-wall of the piston-chamber 23, as is shown in Fig. 1.

The receiver 15 includes a top-wall 40 which is separated from the right side-wall 41 of the said receiver by a longitudinal clearance-passage 42, for purposes as will hereinafter appear. The said top-wall 40 constitutes, in effect, an integral extension of the left side-wall 43 of the receiver 15,

and has its forward portion narrowed as at 44, to leave an opening through which cartridges may be ejected, as is especially well shown in Fig. 12.

The narrow portion 44 of the top-wall 40 terminates short of the forward portion of the receiver and provides a forwardly-facing locking-abutment 45. The forward portion of the right side-wall 41 of the receiver is notched to provide a forwardly-facing locking-abutment 46 which serves in conjunction with the locking-abutment 45, to hold the breech-bolt in its breech-closing position in a manner as will hereinafter appear.

In its left side-wall 43 and below the locking-abutment 45, the receiver 15 is formed on its inner face with a longitudinal guideway in the form of a guide-groove 47 located substantially-diametrically-opposite the clearance-passage 42 between the upper edge of the right side-wall 41 and the right edge of the top-wall 40, before described.

The breech-bolt 20 is formed on its right side adjacent its forward end with the integral combined operating-and-locking lug 37 which is adapted, in a manner as will hereinafter appear, to reciprocate in the clearance-passage 42 in the receiver 15, and to have its rear edge engaged with and disengaged from the locking-abutment 46. The extreme outer portion of the combined operating-and-locking lug 37 is entered into the cam-recess 36 in the rear-head 33 of the action-slide 18, so as to operatively couple the said action-slide to the breech-bolt.

At a point substantially diametrically opposite the operating-and-locking lug 37, the forward portion of the breech-bolt 20 is formed with a locking-lug 48 which is adapted to be engaged with and disengaged from the locking-abutment 45 and to reciprocate in the guide-groove 47 in the left side-wall 43 of the receiver 15.

As is shown especially well in Fig. 11, the breech-bolt 20 is formed with a central-longitudinal passage 49 in which reciprocates and oscillates a firing-plunger 50. The passage 49 just referred to extends from end to end through the breech-bolt 20 and is enlarged adjacent its rear end to provide a rearwardly-facing spring-seat 51 against which is seated the forward end of a helical retracting-spring 52 encircling the adjacent portion of the firing-plunger 50. The opposite or rear end of the retracting-spring 52 seats against a head 53 formed at the rear of the firing-plunger 50 and provided with a helical groove 54, by means of which the retracting-spring 52 may be threaded into a position forwardly of the said head 53. The retracting-spring 52 is accommodated in the enlarged rear portion of the passage 49 in the breech-bolt 20 and serves to yieldingly urge the said firing-plunger rearwardly to withdraw the firing-point 55 at the forward end thereof, into a position wherein it will not engage the primer of a cartridge and also to project the rear end of the said firing-plunger beyond the rear end of the breech-bolt 20.

As is especially well shown in Fig. 7, the breech-bolt is formed in its left side with a longitudinal clearance-slot 56 extending from its rear face to a point adjacent the rear face of the locking-lug 48. The wall portion of the breech-bolt 20 adjacent the forward end of the clearance-slot 56 is cut away to provide a circumferentially-extending clearance-notch 57 intersecting the forward portion of the clearance-slot 56 and like the latter adapted to receive a plate-like guide-stem 58 formed integral with and projecting laterally

from the firing-plunger 50. The said guide-stem 58 is formed at its outer end with a guide-head 59 dimensioned to freely slide in the guide-groove 47 in the left side-wall 43 of the receiver 15.

The rear edge of the guide-stem 58 of the firing-plunger 50 is adapted to engage with a forwardly-facing stop-abutment 60 formed in the breech-bolt 20 and constituting the rear wall of the clearance-notch 57 therein. At the junction of the respective forward walls of the clearance-slot 56 and the clearance-notch 57, the breech-bolt 20 is formed with a cam-like retracting-surface 61 which is adapted to engage with the forward-surface of the plate-like guide-stem 58 to effect the forcible retraction of the firing-plunger in the event of any failure of the retracting-spring 52, all in a manner as will more fully hereinafter appear.

The relatively-slender forward portion of the firing-plunger 50 immediately to the rear of its firing-point 55, is cut away to provide two diverging surfaces 62 and 63 (Figs. 9 and 10). Extending into the cut-away portion of the firing-plunger adjacent the surfaces 62 and 63 just referred to, is the cylindrically-contoured stem 64 of a cartridge-extractor 65. The said stem 64 extends substantially vertically downwardly through the forward portion of the breech-bolt 20 in intersecting relationship with respect to the longitudinal passage 49 which accommodates the firing-plunger 50 in the breech-bolt 20. The angle of the surface 63 on the firing-plunger 20 is such that the said surface will engage with the stem 64 before the guide-stem 58 of the firing-plunger 50 can be brought clear of the stop-abutment 60 and into registration with the longitudinal clearance-slot 56 in the breech-bolt 20. In this manner, the cooperation of the surface 63 with the stem 64 of the cartridge-extractor 65 normally serves to prevent the firing-plunger 50 from being turned sufficiently far to register its guide-stem 58 with the slot 56, so that the rear edge of the guide-stem 58 is retained in position to be engaged with the stop-abutment 60 of the breech-bolt, to thereby limit the rearward travel of the said firing-plunger with respect to the breech-bolt. The removal of the extractor 65 and its integral-stem 64 will enable the firing-plunger to be turned so that its guide-stem 58 will register with the slot 56 in the breech-bolt and thereby permit the rearward withdrawal of the firing-plunger from the breech-bolt 20.

Normally, the breech-bolt 20 may be oscillated with respect to the firing-plunger 50 within the limits substantially represented by the angular displacement of the two diverging surfaces 62 and 63 on the said firing-plunger, as is indicated in Figs. 9 and 10. This scope of relative movement will maintain the rear edge of the guide-stem 58 of the firing-plunger 50 in position to be checked in its rearward movement by its engagement with the stop-abutment 60 on the breech-bolt 20. Normally, the firing-plunger 50 is maintained in its retired position by the tension of the retracting-spring 52, under which condition the rear edge of the guide-stem 58 will be engaged with the stop-abutment 60 of the breech-bolt 20, as is particularly well shown in Figs. 3, 7 and 11.

In the particular firearm chosen for illustration in the accompanying drawings, a hammer 66 is pivotally connected to the rear portion of the trigger-plate unit 17 by means of a pivot-pin 67. The particular form of the hammer 66 or its equivalent, is of no vital import with respect to the present invention but, as shown, the said

hammer is releasably maintained in a cocked position as shown in Fig. 3 by means of a sear 68, and the upper portion of the said hammer is urged to swing forwardly by a suitable hammer-spring 69.

Normally, the retracting-spring 52 serves to maintain the firing-plunger 50 in its retired position in which its firing-point 55 is retired rearwardly of a cartridge such as 70, shown in Figs. 2 and 3. The said retracting-spring 52 also serves to normally hold the rear end of the firing-plunger 50 extended beyond the rear end of the breech-bolt 20 into position to be struck and driven forwardly by the hammer 66.

For purposes of making clear the operation of the above-described firearm, let it be assumed that the hammer 66 is cocked and that the firing-plunger is retracted as shown in Fig. 3. Let it further be assumed that the breech-bolt 20 is moved forwardly from the slightly-retired position shown in Fig. 3 into its full breech-closing position, and is locked therein (Fig. 4) by being turned by the surfaces of the cam-recess 36 in the action-slide 18, so as to cause its combined operating-and-locking lug 37 and its locking-lug 48 to respectively engage with the locking-abutments 46 and 45.

If now the hammer 66 is released to the action of the hammer-spring 69, the upper-portion of the said hammer will swing forwardly and engage with the projecting rear end of the firing-plunger 50 and drive the same forwardly, thereby causing the firing-point 55 to effect the discharge of the cartridge 70. The parts will now have assumed substantially the positions in which they are shown in Fig. 2.

The high-pressure gases developed by the discharge of the cartridge 70 as just above described, will partly flow downwardly through the inclined gas-passage 25 in the cylinder-lug 22, and will drive the piston 27 rearwardly. The rearward movement of the piston 27 will be limited by the ring-like stop-member 30 after but a brief movement, but the energy of the piston will have been imparted to the action-slide 18, and will drive the same rearwardly against the tension of the breech-closing spring 38. The rearward movement of the action-slide 18 will cause the appropriate surfaces of the cam-recess 36 therein, to cooperate with the combined operating-and-locking lug 37 of the breech-bolt 20, to turn the said breech-bolt from the position in which it is shown in Figs. 2 and 4 into the position in which the said breech-bolt is shown in Figs. 3 and 5. The turning movement of the breech-bolt just referred to, will disengage the lug 37 and the lug 48 thereof from their respective cooperating locking-abutments 46 and 45, thereby bringing the lugs 37 and 48 respectively into registry with the clearance-passage 42 and the guide-groove 47 in the receiver 15.

Should the retracting-spring 52 of the firing-plunger 50 have failed to act for any reason to retire the said firing-plunger, the turning movement of the breech-bolt above referred to, will cause the retracting-surface 61 of the breech-bolt to engage with the forward edge of the guide-stem 58, and thereby forcibly retire the said firing-plunger, so that its firing-point 55 will be drawn rearwardly (Fig. 3) out of position wherein it can engage with the primer of a cartridge. Thus, in the event that the retracting-spring 52 of the firing-plunger 50 should become damaged, or should the firing-point 55 become so wedged in a defective primer as to render the said re-

tracting-spring ineffective, the said firing-plunger will be forcibly and positively retracted by the turning movement of the breech-bolt. This turning movement of the breech-bolt relative to the firing-plunger is possible, due to the fact that the guide-head 59 of the firing-plunger is held against turning movement by riding in the guide-groove 47 in the left side-wall 43 of the receiver 15. Thus, while the said firing-plunger is free to move longitudinally with the breech-bolt 20 and also longitudinally with respect thereto, the said firing-plunger is held against turning movement relative to the receiver when the breech-bolt itself is turned with respect to the said receiver.

Following the initial turning movement of the breech-bolt to unlock the same as above described, its movement will continue rearwardly in the normal manner of firearms until the just-fired cartridge has been extracted and ejected, 20 and the hammer 66 has again been cocked. Following the rearward movement of the breech-bolt 20 into its fully retired position, the breech-closing spring 38 will assert itself and move the action-slide 18 forwardly and thereby also move 25 the breech-bolt 20 forwardly, and will ultimately cause the said action-slide to turn the said breech-bolt to again lock the same in its breech-closing position preparatory to another cycle of operation of the firearm.

The firearm may be operated manually, if desired, by means of the operating-handle 35 extending laterally from the action-slide 18.

From the foregoing it will be seen, that by means of the present invention, an effective construction and arrangement of parts is provided, whereby it is insured that the firing-point 55 or its equivalent will be in its retired position when the breech-bolt is moving forwardly, to thereby avoid the accidental discharge of a fresh cartridge prior to the said cartridge having been fully seated and the said breech-bolt having been fully closed and locked in its breech-closing position.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A bolt-action firearm, including in combination: a receiver formed with a bolt-receiving chamber and with a longitudinally-extending guideway located adjacent the said chamber; a breech-bolt having both reciprocating and turning movement in the bolt-receiving chamber of the said receiver, the said breech-bolt having a longitudinal plunger-receiving passage therein and also having a longitudinal clearance-slot intersecting its rear end and a clearance-passage laterally intersecting the said clearance-slot, the said clearance-passage having a rear wall providing a forwardly-facing stop-abutment terminating at one end at the said clearance-slot, the said breech-bolt also being formed in a forward portion of its said clearance-passage with an inclined retracting-cam surface facing generally rearwardly; a firing-plunger mounted in the plunger-receiving passage of the said breech-bolt and having a lateral projection extending outwardly through the clearance-passage in the said

5 breech-bolt for engagement with the retracting-cam surface and the stop-abutment thereof and having sliding engagement in the guideway of the said receiver, the firing-plunger having a laterally-facing limiting-abutment and having relative turning movement with respect to the said breech-bolt; spring-means urging the said firing-plunger rearwardly; and releasable limiting-means carried by the said breech-bolt and positioned to be engaged by the laterally-facing limiting-abutment of the said firing-plunger before the lateral projection of the said firing-plunger can pass out of engagement with the forwardly-facing stop-abutment in the clearance-passage of the breech-bolt to thus prevent the inadvertent rearward movement of the lateral projection of the said firing-plunger through the longitudinal clearance-slot in the said breech-bolt under the urge of the said spring-means.

2. A bolt-action firearm, including in combination: a receiver formed with a bolt-receiving chamber and with a longitudinally-extending guideway located adjacent the said chamber; a breech-bolt having both reciprocating and turning movement in the bolt-receiving chamber of the said receiver, the said breech-bolt having a longitudinal plunger-receiving passage therein and also having a longitudinal clearance-slot intersecting its rear end and a clearance-passage laterally intersecting the said clearance-slot, the said clearance-passage having a rear wall providing a forwardly-facing stop-abutment terminating at one end at the said clearance-slot, the said breech-bolt also being formed in a forward portion of its said clearance-passage with an inclined retracting-cam surface facing generally rearwardly; a firing-plunger mounted in the plunger-receiving passage of the said breech-bolt and having a lateral projection extending outwardly through the clearance-passage in the said breech-bolt for engagement with the retracting-cam surface and the stop-abutment thereof and having sliding engagement in the guideway of the said receiver, the firing-plunger having a laterally-facing limiting-abutment and having relative turning movement with respect to the said breech-bolt; spring-means urging the said firing-plunger rearwardly; and a cartridge-extractor 30 carried by the said breech-bolt and having a stem extending transversely of the breech-bolt and positioned to be engaged by the laterally-facing limiting-abutment of the said firing-plunger before the lateral projection of the said firing-plunger can pass out of engagement with the forwardly-facing stop-abutment in the clearance-passage of the breech-bolt to thus prevent the inadvertent rearward movement of the lateral projection of the said firing-plunger through the longitudinal clearance-slot in the said breech-bolt under the urge of the said spring-means.

3. A bolt-action firearm, including in combination: a receiver formed with a bolt-receiving chamber and with a longitudinally-extending guideway located adjacent the said chamber, the said receiver also having a locking-recess laterally intersecting the said guideway; a breech-bolt having both reciprocating and turning movement in the bolt-receiving chamber of the said receiver and provided with a laterally-projecting locking-lug movable in both the guideway and the locking-recess of the said receiver, the said breech-bolt having a longitudinal plunger-receiving passage therein and also having a longitudinal clearance-slot intersecting its rear end

and a clearance-passage laterally intersecting the said clearance-slot, the said clearance-passage having a rear wall providing a forwardly-facing stop-abutment terminating at one end at the said clearance-slot, the said breech bolt also being formed in a forward portion of its said clearance-passage with an inclined retracting-cam surface facing generally rearwardly; a firing-plunger mounted in the plunger-receiving passage of the said breech-bolt and having a lateral projection extending outwardly through the clearance-passage in the said breech-bolt for engagement with the retracting-cam surface and the stop-abutment thereof and having sliding engagement in the guideway of the said receiver, the firing-plunger having a laterally-facing limiting-abutment and having relative turning movement with respect to the said breech-bolt; spring-means urging the said firing-plunger rearwardly; and releasable limiting-means carried by the said breech-bolt and positioned to be engaged by the laterally-facing limiting-abutment of the said firing-plunger before the lateral projection of the said firing-plunger can pass out of engagement with the forwardly-facing stop-abutment in the clearance-passage of the breech-bolt to thus prevent the inadvertent rearward movement of the lateral projection of the said firing-plunger through the longitudinal clearance-slot in the said breech-bolt under the urge of the said spring-means.

4. A bolt-action firearm, including in combination: a receiver formed with a bolt-receiving chamber and with a longitudinally-extending guideway located adjacent the said chamber, the said receiver also having a locking-recess laterally intersecting the said guideway; a breech-bolt having both reciprocating and turning movement in the bolt-receiving chamber of the

said receiver and provided with a laterally-projecting locking-lug movable in both the guideway and the locking-recess of the said receiver, the said breech-bolt having a longitudinal plunger-receiving passage therein and also having a longitudinal clearance-slot intersecting its rear end and a clearance-passage laterally intersecting the said clearance-slot, the said clearance-passage having a rear wall providing a forwardly-facing stop-abutment terminating at one end at the said clearance-slot, the said breech-bolt also being formed in a forward portion of its said clearance-passage with an inclined retracting-cam surface facing generally rearwardly; a firing-plunger mounted in the plunger-receiving passage of the said breech-bolt and having a lateral projection extending outwardly through the clearance-passage in the said breech-bolt for engagement with the retracting-cam surface and the stop-abutment thereof and having sliding engagement in the guideway of the said receiver, the firing-plunger having a laterally-facing limiting-abutment and having relative turning movement with respect to the said breech-bolt; spring-means urging the said firing-plunger rearwardly and a cartridge-extractor carried by the said breech-bolt and having a stem extending transversely of the breech-bolt and positioned to be engaged by the laterally-facing limiting-abutment of the said firing-plunger before the lateral projection of the said firing-plunger can pass out of engagement with the forwardly-facing stop-abutment in the clearance-passage of the breech-bolt to thus prevent the inadvertent rearward movement of the lateral projection of the said firing-plunger through the longitudinal clearance-slot in the said breech-bolt under the urge of the said spring-means.

DAVID M. WILLIAMS.
